[57] CLAIM

The ornamental design for a display stand for rug samples or similar article, as shown and described.

DESCRIPTION

FIG. 1 is a perspective view of a display stand for rug samples or similar article showing my new design;

FIG. 2 is a top plan view thereof;

FIG. 3 is a front elevational view thereof;

FIG. 4 is a rear elevational view thereof; the broken line showing of rug samples is for illustrative purposes only and forms no part of the claim design; and

FIG. 5 is a bottom plan view thereof.
